United States Patent Office

Des. 184,408
Patented Feb. 10, 1959

184,408

CHILD'S TOILET SEAT

Curtis F. Pearl, West Englewood, N. J., assignor to Zadek Feldstein Co. Inc., New York, N. Y., a corporation of New York

Application September 24, 1958, Serial No. 52,749

Term of patent 14 years

(Cl. D4—5)

Fig. 1 is a perspective view looking toward the front of the toilet seat;

Fig. 2 is a rear elevation;

Fig. 3 is a side elevation of the toilet seat.

I claim:

The ornamental design for a child's toilet seat, as shown.
